UNITED STATES PATENT OFFICE.

WILLIAM T. WOOD, OF WASHINGTON, DISTRICT OF COLUMBIA.

PAPER-FILE.

SPECIFICATION forming part of Letters Patent No. 341,394, dated May 4, 1886.

Application filed May 15, 1885. Serial No. 105,018. (No model.)

To all whom it may concern:

Be it known that I, WILLIAM T. WOOD, a citizen of the United States, residing at Washington city, in the District of Columbia, have 5 invented certain new and useful Improvements in Paper-Files, of which the following is a specification.

My invention consists in providing a cheap substantial article for the compression and 10 preservation of papers, which, from its simplicity of construction, will greatly facilitate filing of papers and enable easy access to the same. I attain these objects by the mechanism illustrated in the accompanying drawings, 15 which are explained in the description of my invention, as hereinafter set forth.

The invention is fully illustrated in the accompanying drawings, which form a part of the specification, and in which— 20 Figure 1 represents a perspective view of a file-box complete, made entirely of wood, except the clamping device and metal plate secured to the follower. In this construction I show the side bars or rods connected with 25 wooden posts *a*, rising from the rear corners of the bottom. The box, however, may be made of metal, in which case the side rods may be bent down and fastened directly to the bottom of the file-box, dispensing with the 30 posts *a*.

Fig. 2^A is a rear elevation of the clamping device. Fig. 2^B is a top view of the clamping device, showing the neck *d* and lugs *e*. Fig. 2^C is a side view of part of the clamping device. Fig. 3^A is a rear elevation of the slotted plate which is fastened to the back of the 35 follower. Fig. 3^B is a side view of the slotted plate, showing the hinged connection with the clamping device.

40 The paper-file or file-box described has a front and bottom of suitable proportions. Plain-surfaced bars or rods run parallel with the bottom on both sides of the file-box, having their ends secured to the front and bottom. 45 Between the side rods is placed a follower, *E*, which is to be moved backward and forward by means of a clamping device, constructed and arranged and operated as hereinafter described.

50 My clamping device is provided with per-

forated openings or eyelets to slide along the side rods of the file-box, one end of the device being secured to the follower, to enable its backward and forward movement.

Between the part of the clamping device 55 which is attached to the follower and the eyelet which moves upon the side rod the clamping device is curved, so as to admit of a free movement of the eyelet part upon the side rod when the follower is free; but when the follower is pressed against the papers the eyelets will tilt or incline, grasping the plain-surfaced side rods and holding the follower securely at any desired pressure. The follower is freed from pressure by a slight movement of the 55 clamping device, to enable addition, change, or examination of papers.

For convenience in detaching the follower from the clamping device, I form a neck, *d*, and lugs *e* near the end of my clamping device, 70 which is attached to a slotted plate fastened securely to the follower. The lugs and neck are inserted in the slotted plate, and a hinged attachment of follower and clamping device is secured, to enable the desired backward and 75 forward movement of the follower.

The detachment is effected by so moving the follower that the lugs on the clamping device will be parallel with the slot in the plate and admit of easy detachment. 80

There are other well-known methods of attaching or hinging the clamping device to the follower. The lugs and slotted plate are not an essential feature of my clamping device, except where easy detachment of clamping device and follower is desired. 85

In the construction of my paper-file or file-box I use no form of metal casting provided with indentations, corrugations, or ratcheted plates, either as side bars or on the base of my 90 file-box.

My invention relates to file-boxes whose sides I provide with plain-surfaced rods of wood or metal.

Other modifications of my file-box may be 95 made in detail of construction without sacrificing the principles of my invention, the essential features of which are a clamping device provided with perforated openings or eyelets fashioned to slide freely on the side rods 100

of the file-box, with a loose hinged attachment connecting the follower and clamping device, operated as shown and described.

What I claim, and desire to secure by Letters Patent, is—

1. A clamping device for file-boxes having a projecting arm or lever which hinges to or connects the follower and clamping device, the latter being provided with perforated openings or eyelets fashioned to slide upon and grasp or clamp the plain-surfaced side rods, as shown and described.

2. In a file-box, the combination of a follower and clamping device, the two connected together by a loose joint, the clamping device provided with openings or eyelets which slide on plain-surfaced rods or side bars of the file-

box, and adapted by the loose joint to turn upon said rods and clamp the same, as shown and described.

3. A slotted plate on the back of the follower, fashioned to receive the neck and lugs on the arm or lever of the clamping device, admitting of free movement of the lugs and neck in the slotted plate, also enabling easy detachment of the follower and clamping device, as shown and described.

In testimony whereof I affix my signature in the presence of two witnesses.

WILLIAM T. WOOD.
